(57) **CLAIM**

The ornamental design for a case for electronic device, as shown and described.

DESCRIPTION

FIG. 1 is a front, top, and side perspective view of a case for electronic device showing the new design;

FIG. 2 is a front elevation view of the case for electronic device of FIG. 1;

FIG. 3 is a back elevation view of the case for electronic device of FIG. 1;

FIG. 4 is a side elevation of the case for electronic device of FIG. 1;

FIG. 5 is an opposite side elevation view of the case for electronic device of FIG. 1;

FIG. 6 is a top plan view of the case for electronic device of FIG. 1; and,

FIG. 7 is a bottom plan view of the case for electronic device of FIG. 1.

The broken lines shown in the drawings depict portions of the case for electronic device that form no part of the claimed design.
